Primary Examiner — Prabhakar Deshmukh(74) *Attorney, Agent, or Firm* — David A. Burge(57) **CLAIM**

I claim the ornamental design for a combination controlled cash bag lock, substantially as shown and described.

DESCRIPTION

FIG. 1 is a left end view of a combination controlled cash lock showing my new design;

FIG. 2 is a top view thereof;

FIG. 3 is a front side view thereof, it being understood that a rear side view is a mirror image thereof;

FIG. 4 is a left end view thereof; and,

FIG. 5 is a right end view thereof.

The broken lines environment is for illustrative purposes only and forms no part of the claimed design.
